CUTTING AND COOLING LUBRICANT

John C. Zimmer, Hillside, and John B. Holtzclaw,
Roselle, N. J., assignors to Standard Oil De-
velopment Company, a corporation of Delaware

No Drawing. Application August 19, 1936,
Serial No. 96,812

4 Claims. (CL 87-9)

This invention relates to an improved lubricating composition and more particularly to compositions adapted for lubrication and cooling of surfaces operated at high speeds and pressures, 5 such as are used in metal cutting operations.

In the past, water solutions or emulsions of soluble cutting oils prepared from sulfonate soaps and the so-called sulfo-naphthenates extracted from petroleum sludge have been used extensively 10 in the metal fabricating industry for the lubrication and cooling of metal cutting tools in slow speed turning, drilling, grinding and similar operations on malleable and other soft irons and steel, primarily for cooling or heat dissipation. 15 High speed cutting, however, demands more oily lubricants to prevent chattering, welding of the tool to the work and to prolong tool life to a reasonable period. These aqueous emulsions have not proven satisfactory in such high speed operation, particularly on tough alloy steels, and the metal industry has used almost universally in the past a water-free lubricant such as lard oil, sulfurized lard or other fatty oils or mixtures of sulfurized fatty oil and sulfurized mineral oil. 20 These materials provide the additional oiliness required but are greatly inferior to water emulsions in cooling or heat absorbing capacity.

It has now been found that higher production speed, longer tool life and a better finish on the work can be obtained in metal working, particularly in high speed operations on tough alloy steels, by using an improved lubricating composition comprising an aqueous emulsion of an extreme pressure lubricant or cutting oil such as a sulfurized fatty oil. By this means the high film strength and high lubricity or oiliness of the sulfurized oils is combined with the heat absorbing properties of aqueous emulsions in the form of a stable emulsion which is non-corrosive to steel even at elevated temperatures and which 35 possesses extreme pressure lubrication and high film strength properties equal even to the best commercial straight sulfurized cutting oils. Stable emulsions having these properties are secured even when the composition of the present invention is diluted with from 10 to 20 parts of water to one part of the lubricant base.

The composition of the present invention contains about 50 to 90% of a mineral oil, preferably a petroleum lubricating oil having a viscosity below about 500 seconds Saybolt Universal at 100° F., although more viscous oils can be used. It also contains a suitable proportion of a sulfurized fatty oil to impart the desired high film strength characteristics. The amount of this sulfurized fatty oil may vary widely depending upon the operating conditions to which the composition is to be subjected and a concentration between 55 about 1 and 20% will be found sufficient for most

purposes. The preferred concentration is about 5 to 15%.

The sulfurized oil may be prepared by any suitable method in use for introducing sulfur into the organic molecule in a form imparting extreme pressure lubrication characteristics thereto. One suitable method is to heat a mixture of the lard oil with preferably from 10 to 20% of flowers of sulfur, with stirring, to a temperature of about 350 to 450° F. The sulfurized oil preferably contains about 5 to 25% by weight of sulfur. It is preferably added to the cutting oil base in such proportion as to impart to it about 1 to 5% of sulfur.

Other sulfurized oils may be used in place of the sulfurized lard oil, such as the fatty oils of vegetable, animal and marine origin, also the fatty acids derivable from such oils, and the acids of similar molecular weight obtained by the limited oxidation of paraffin wax at low tem- 15 peratures.

The composition also contains a suitable proportion of an emulsifying agent to render it readily miscible or emulsifiable with water. Any suitable agent for preparing emulsions of oil and water may be used which is not objectionably corrosive to metal surfaces. Examples of such emulsifying agents are the mahogany soaps derived from the treatment of petroleum oils with strong or fuming sulfuric acid, naphthenic acid soaps such as those derived from petroleum crudes containing naphthenic acids, sulfonaphthenic acids, such as those obtained by the treatment of naphthenic base oils with strong or fuming sulfuric acid followed by the recovery from the oil of the resulting mixture of organic acids, also the ordinary fatty oil soaps of fatty acids with suitable metals, preferably ammonium and the alkali metals sodium and potassium, and also similar soaps of wax acids, i. e., acids obtained by the limited oxidation of paraffin wax at low 20 25 30 35 40 45 50 55 60 65 70 75 80 85 90 95 100 105 110 115 120 125 130 135 140 145 150 155 160 165 170 175 180 185 sium hydroxide, soda ash or carbonates. Generally a fraction of 1% of the alkali is sufficient. A small amount of water, from about $\frac{1}{2}$ to 3%, may be used and aids in carrying the alkali into the solution.

Example I

The following example is presented in order to illustrate a suitable embodiment of this invention but is not intended to limit this invention in any way:

	Percent
Mineral oil—100 seconds Saybolt viscosity at 100° F.	59.1
Sulfurized lard oil	10.0
15 Mahogany soap	22.0
Diethylene glycol	2.0
Rosin	4.3
Caustic soda	0.6
Water	2.0

20 In the above example the mahogany soaps consist of a 50% solution by volume of oil soluble sodium sulfonates in oil, which is preferably a mineral lubricating oil of about 75 to 500 seconds Saybolt Universal viscosity at 100° F.

25 The above composition, when diluted with 16 volumes of water to one volume of this composition carries the full load of 15,000 pounds per square inch on the Almen machine, using steel 30 to steel bearings, with a maximum friction of 30 pounds inches. Similar compositions containing ordinary (unsulfurized) lard oil, carry only 3,000 to 6,000 pounds per square inch in this test.

Example II

35 The following tests were conducted to compare the effectiveness of this composition with emulsions of non-sulfurized cutting oils. Closely comparative tests were made in cutting a standard steel, and tool life was measured at several 40 different cutting speeds. The results are presented in the table below.

45 Lubricant A is an emulsion, in ten parts of water, of one part of the composition described in Example I. Lubricant B is an emulsion, in ten parts of water, of one part of the same composition, omitting the sulfurized lard oil and diethylene glycol.

	Tool life at various cutting speeds	
	Cutting speeds feet/minute	Tool life minutes
55 Lubricant A		
Do.	110	210
Do.	120	87
Do.	130	38
Lubricant B		
Do.	110	102
Do.	120	50
Do.	130	25

In these tests, the applicants' composition (A) gave entirely satisfactory operation and showed no tendency to corrode or rust the metal surfaces. Tool lives 50 to 100% greater than those with the sample B were obtained. In contrast 5 with these results, emulsions prepared from sulfurized mineral oil or sulfurized sulfonates severely corrode steel even at ordinary temperatures within a few hours.

While straight, or water-free, cutting oil compositions possess some advantages over sample B, they are much more expensive than the applicants' composition and are greatly inferior as cooling agents. The use of applicants' emulsion accordingly permits rapid cutting at lower temperatures and safer and more accurate work.

This invention is not to be limited by any specific examples or explanations presented herein, all of which are intended solely for purpose of illustration, but is to be limited only by the following claims, in which it is desired to claim all novelty insofar as the prior art permits.

We claim:

1. An alkaline oleaginous composition suitable for emulsification with water to form a cutting and cooling composition comprising about 50 to about 90% of a mineral lubricating oil, about 1 to about 20% of a sulfurized fatty oil, about $\frac{1}{2}$ to about 3% of a glycol ether, about $\frac{1}{2}$ to about 3% of water, about 1 to about 30% of 30 mahogany soaps, about $\frac{1}{2}$ to about 10% of rosin and containing, also, about 0.6% of a strong alkali.

2. A cutting and cooling oil composition comprising an emulsion with about 10 to about 20 volumes to water of one volume of an alkaline mixture containing about 80% of a mineral lubricating oil, about 20% of a water-soluble soap as an emulsifying agent, about 10% of a sulfurized fatty oil, about 5% of rosin, about $\frac{1}{2}$ to about 3% of a glycol ether and about 0.6% of a strong alkali.

3. An alkaline oleaginous base emulsifiable with alkali to form a cutting and cooling composition comprising about 81% of a mineral lubricating oil, about 22% of mahogany soaps, about 10% of sulfurized lard oil, about 4.3% of rosin, about 0.6% of caustic soda, about 2% of diethylene glycol and about 2% of water.

4. An alkaline cutting oil base emulsifiable 50 with water consisting of about 60% of mineral oil having 100 seconds Saybolt viscosity at 100° F., 10% of a sulfurized lard oil, 22% of a mahogany soap, 2% of diethylene glycol, 4.3% of rosin, 0.6% of caustic soda and 2.0% of water.

JOHN C. ZIMMER.
